RAZOR

Edward J. Youmans, Barley, Ga.

Application November 9, 1932. Serial No. 641,909

7 Claims. (Cl. 30—12)

This invention relates to new and useful improvements in razors and more particularly to razors of the safety type.

The principal object of the present invention is to provide a safety razor having a special guard construction in the use of which beard will be guided toward the blade at an oblique angle so that the beard will wipe against the edge of the blade, resulting in a better cutting action than when the beard meets the blade edge from a right angular direction.

Another object of importance of the invention is to provide a guard for safety razors wherein the teeth of the guard are capable of being adjusted to various angular positions with respect to the blade with which the guard is used, this being especially practical for cutting various kinds of beard growths.

Other objects reside in the provision of means whereby clogging space between the guard teeth and the blade is eliminated and wherein the frame of the razor is sufficiently ductile to permit adjusting and proper setting of the guard teeth assembled with respect to the blade.

Numerous other important objects and advantages of the invention will become apparent to the reader of the following specification.

In the drawing:—

Figure 1 represents a top plan view of a razor with the improved guard.

Fig. 2 represents a side elevational view of the guard on a razor.

Fig. 3 represents a fragmentary vertical sectional view through the guard and part of the handle construction.

Fig. 4 is a fragmentary top plan view of the razor shown in Fig. 1, showing the teeth in full lines and broken lines to the limits they are adjustable.

Fig. 5 represents a top plan view of the stamping of which the guard frame is constructed.

Fig. 6 represents a top plan view of the bridge piece which connects the ends of the frame.

Fig. 7 represents a perspective view of one of the teeth elements.

Fig. 8 represents a fragmentary perspective view showing the intermediate portion of one of the teeth connecting bars.

Referring to the drawing wherein like numerals designate like parts, it can be seen that numeral 5 represents the cap plate provided with the threaded shank 6 which is engageable into the threaded socket 7 located in the tapering end 8 of the handle 9. The foregoing are conventional elements of a safety razor, although it is to be

borne in mind that the specific shape of the handle 9 with its tapered end 8 has utility in the present invention.

The novel guard generally referred to by numeral 10 as shown in Fig. 5 has its frame constructed of a single sheet of metal. In considering Fig. 5, it can be seen that the U-shaped members 11—11 are bent upwardly as shown in Fig. 3 as are the side walls 12—12. It can be seen that when the side walls 12—12 have been bent upwardly and the upper flange 13 thereof bent inwardly, the frame is ready to have the teeth assembled therewith. The side walls 12 are provided with the lower flanges 14 and both the upper and lower flanges 13 and 14 respectively are provided with a plurality of corresponding openings 15. Extending vertically through the openings 15 of these flanges are the reduced shank portions 16 of the teeth 17, the teeth 17 at the points where they merge with the shank portions 16 being provided with shoulders 18 for rest upon the upper flanges 13 in the manner substantially shown in Fig. 3. The lower portion of each tooth 17 is provided with a laterally disposed crank-like portion 19 and a depending pintle 20 at its extremity.

Again referring to the frame, it can be seen that the lower flanges 14 are connected by the cross members 21—21 and it is obvious that in the event the teeth 17 are located too far inwardly of the cutting edges of the blade 22, a screw driver or like instrument can be used to pry the side walls 12 slightly outwardly and obviously this carries with it the corresponding group of teeth.

Fig. 6 discloses a bridge piece consisting of a pair of elongated members 22 connected by cross members 23 at their ends, the elongated members 22 being in spaced relation and having notched portions 24 defining a passageway 95 through which the threaded shank 6 of the cap plate 5 can extend and in the manner substantially shown in Fig. 3. The cross members 23—23 are soldered, welded, or otherwise secured to the bight portions of the U-shaped members 11—11 100 of the frame 10.

A pair of connecting bars 25 are employed, each provided with a plurality of longitudinally spaced openings 26 and with a cavity 27 in one edge portion thereof.

As is clearly apparent in Fig. 3, there is a group of these teeth 17 on each side of the guard and the pintles 20 of each group extend downwardly to pass thru the openings 26 in the corresponding connecting bar 25.

105

110

In the use of the razor with this novel guard, it can be seen that the teeth 17 are first set to the proper angle with respect to the blade 22 while the handle 9 is loose on the cap plate screw 5. Now by tightening or screwing in the handle 9, the tapered portion 8 will ride against the concave portion 27 of the connecting bars 25—25 and in engaging the same will frictionally retain these bars against self-adjusting, thus retaining the teeth in a set predetermined angle with respect to the razor blade. (See Fig. 3.)

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

20 1. In a razor of the safety type, a cap plate, a handle having a tapered end provided with a threaded socket, a screw projecting from the cap plate and adapted to engage into the threaded socket of the handle, swingable guard teeth, a connector for the guard teeth, said tapered portion of the handle being wedgeable against the said connector when the said handle is fed inwardly on the screw of the cap plate.

30 2. In combination, a razor comprising a handle, a cap plate, a guard frame, means between the cap plate and the handle for clamping a blade between the cap plate and the guard frame, and adjustable guard teeth on the said frame adjustable angularly with respect to the cutting edge 35 of the blade and on substantially the same plane as the blade.

3. In combination, a razor comprising a handle, a cap plate, a guard frame, means between the cap plate and the handle for clamping a 40 blade between the cap plate and the guard frame, adjustable guard teeth on the said frame, said teeth being each provided with a shaft-like shank rotatably disposed through the frame, and means whereby the said shaft-like shanks can be rotated.

4. In combination, a razor comprising a handle, a cap plate, a guard frame, means between the cap plate and the handle for clamping a

50

blade between the cap plate and the guard frame, adjustable guard teeth on the said frame, said teeth being each provided with a shaft-like shank rotatably disposed through the frame, means whereby the said shaft-like shanks can be rotated, simultaneously.

5. In combination, a razor comprising a handle, a cap plate, a guard frame, means between the cap plate and the handle for clamping a blade between the cap plate and the guard frame, adjustable guard teeth on the said frame, said teeth being each provided with a shaft-like shank rotatably disposed through the frame, means whereby the said shaft-like shanks can be rotated simultaneously, said means comprising a crank extension on each of the said shanks and a connector between the said extensions.

6. In combination, a razor comprising a handle, a cap plate, a guard frame, means between the cap plate and the handle for clamping a blade between the cap plate and the guard frame, adjustable guard teeth on the said frame, said teeth being each provided with a shaft-like shank, rotatably disposed through the frame, means whereby the said shaft-like shanks can be rotated simultaneously, said means comprising a crank extension on each of the said shanks and a connector between the said extensions, and means for retaining the connector and the associated teeth in adjusted position.

7. In combination, a razor comprising a handle, a cap plate, a guard frame, means between the cap plate and the handle for clamping a blade between the cap plate and the guard frame, adjustable guard teeth on the said frame, said teeth being each provided with a shaft-like shank, rotatably disposed through the frame, means whereby the said shaft-like shanks can be rotated simultaneously, said means comprising a crank extension on each of the said shanks and a connector between the said extensions, means for retaining the connector and the associated teeth in adjusted position, said means consisting of a taper on the handle ridable against the connector for frictionally engaging and retaining the connector against self motion.
